PORTABLE BARBECUE

Frederick J. Erickson, 3910 51st St.,
Des Moines, Iowa 50130

Filed Aug. 30, 1973, Ser. No. 392,865

Term of patent 14 years

Int. Cl. D7—02

U.S. Cl. D7—110

Fig. 1

Fig. 2

Fig. 4

Fig. 3

Fig. 5

Fig. 6

Fig. 7

FIG. 1 is a front perspective of a portable barbecue showing my new design;

FIG. 2 is a front elevational view thereof;

FIG. 3 is a side elevational view thereof;

FIG. 4 is a rear elevational view thereof;

FIG. 5 is a bottom view;

FIG. 6 is an elevational view of the side opposite the side shown in FIG. 3; and

FIG. 7 is a top view.

I claim:

The ornamental design for a portable barbecue, substantially as shown.
